PACKING BENCH

Donald F. Mercer, Toledo, Ohio, assignor to
 Libbey-Owens-Ford Glass Company, Toledo,
 Ohio, a corporation of Ohio

Application December 13, 1939, Serial No. 308,918

8 Claims. (Cl. 226—129)

This invention relates to packing benches generally and, while not limited thereto, relates more particularly to benches for use in the packing of glass sheets or similar articles.

The term "glass sheets" as herein employed is intended to include sheets of window glass, plate glass, laminated safety glass, tempered glass, ornamental structural glass, etc., as well as sheets or plates of similar material.

In the packing of glass sheets for shipment, it is common practice to insert sheets of paper between adjacent glass surfaces which would otherwise contact with one another in order to prevent chemical or physical damage which sometimes occurs when glass contacts with glass.

According to one method of packing glass sheets for shipment, such as for example sheets of laminated safety glass, it is customary to use relatively large wooden shipping boxes and to stack the sheets on edge in the box, with sheets of paper inserted between adjacent glass surfaces. This packing is performed manually, with the operator first picking up a sheet of safety glass from a buck and placing it within the box, then placing a sheet of paper against the exposed glass surface, after which a second sheet of safety glass is laid against the paper, and so on. It has heretofore been the usual practice to place a stack of paper sheets either in the box, upon the glass, or at some other place where the sheets could be picked up by the operator and inserted between the glass sheets. However, no definite place has been provided for the paper sheets within convenient reach of the operator, with the result that they were unhandy and inconvenient to the operator and resulted in the expenditure of more time and effort in the packing of the glass. An important object of this invention is the provision of a novel and improved packing bench for supporting the wooden shipping boxes in a convenient manner during the packing of the glass sheets therein and so constructed as to facilitate the inserting of sheets of paper by the operator between adjacent glass surfaces.

Another important object of the invention is the provision of a packing bench having means for supporting the top of the shipping box in open, substantially horizontal position so that it forms a shelf or platform upon which the stack of paper sheets may be carried within handy, convenient reach of the operator.

A further important object of the invention is the provision of a packing bench of the above character wherein the means for supporting the

top of the shipping box is adjustable to accommodate boxes of various sizes.

Other objects and advantages of the invention will become more apparent during the course of the following description, when taken in connection with the accompanying drawing.

In the drawing, wherein like numerals are employed to designate like parts throughout the same:

Fig. 1 is a side elevation of a packing bench constructed in accordance with the present invention; and

Fig. 2 is a rear view thereof.

With reference to the drawing, the improved packing bench herein provided is designated in its entirety by the letter A and is adapted to support the shipping box B during the packing of the glass sheets therein. The shipping box may of course be of any suitable construction but is preferably of wood and provided with a top 5 which may be hingedly connected to one side of the box by wires or the like 6. The packing bench embodies means for supporting the top 5 of the box B in open, substantially horizontal position, as shown in Fig. 1, so that the said top forms a shelf or platform upon which a stack of paper sheets 7 may be laid. These paper sheets are thus placed within handy, convenient reach of the operator and are adapted to be inserted between the glass sheets as they are stacked on edge within the box as indicated at 8.

In the embodiment illustrated in the drawing, the packing bench A is rectangular and comprises the vertical front and rear walls 9 and 10 connected together at their opposite ends by the end walls 11 and 12 and also intermediate their ends if desired by similar bracing members 13. The end walls 11 and 12 and intermediate bracing members 13 are cut out at their upper ends to provide the rearwardly and downwardly inclined edges 14 and the upwardly and rearwardly inclined edges 15 which extend at substantially right angles to edges 14. As a result of this construction, the front wall 9 is relatively shorter than the rear wall 10.

Secured upon the inclined edges 14 of the end walls 11 and 12 and intermediate bracing members 13 is a bottom member 16 which also inclines rearwardly and downwardly from the front wall 9, while secured to the upwardly and rearwardly inclined edges 15 is a similarly inclined back member 17; said back member being spaced at its upper end from the rear wall 10 and secured thereto by a longitudinal bracing strip 18. The back member 17 is arranged at substantially

right angles to the inclined bottom member 16 and cooperates therewith to form a cradle for receiving the shipping box B. As shown in Fig. 1, the shipping box B is supported in an inclined position upon the bottom member 16, with one side thereof engaging the back member 17. Thus, when the glass sheets 8 are stacked on edge within the box they will also assume an inclined position, as indicated in broken lines, so that the chances of them falling or slipping forwardly during packaging will be minimized.

Although the packing bench may be stationary, it is preferably mounted upon rollers or casters 19 and 20 so that it can be shifted from place to place as desired. The rollers 19 and 20 are carried at the opposite ends of longitudinally extending boards 21 and 22 respectively secured to the bottom edges of the front and rear walls 9 and 10 as well as to the end walls 11 and 12 and intermediate bracing members 13.

The means for supporting the top 5 of the shipping box B in open, substantially horizontal position comprises the two spaced head-stocks carried by the rear wall 10 of the bench and designated in their entirety by the numerals 23 and 24. Each head-stock comprises a pair of spaced vertical strips 25 and 26 secured to the rear wall 10 in any desired manner, such as by nails, screws, or the like. Extending between and secured to the strips 25 and 26 is a plate 27 which cooperates with the said strips to provide a vertical guideway therebetween. Slidably received within this guideway is a vertical bar 28, to the upper end of which is secured a transverse head member 29, the upper face of which is preferably beveled as at 30.

The head blocks 29 are adapted to be disposed above the rear wall 10 of the bench to support the top 5 of the shipping box in open, substantially horizontal position. The stack of paper sheets 7 can then be laid upon the top 5 so that they are within handy, convenient reach of the operator during the packing of the glass sheets. In this way, the inserting of the paper sheets between adjacent glass surfaces by the operator is greatly facilitated, as a result of which the packing can be more quickly and neatly accomplished with a minimum amount of effort and lost motion.

The head members 29 are adjustable vertically to take care of shipping boxes of different sizes and may be secured in properly adjusted position by any suitable means. As herein shown, however, each bar 28 is provided with a plurality of vertically spaced openings 31 which may be selectively brought into registry with an opening 32 in the plate 27. Inserted through the opening 32 and the desired opening 31 is a pin 33 which for convenience may be carried by a chain 34 secured to the rear wall 10 as at 35. After the head member 29 is raised to the desired location, the pin 33 is passed through the opening 32 and also through the aligned opening 31 to hold the head member in adjusted position. One size of shipping box B is shown in full lines in Fig. 1, and when using this size box the head members 29 of the head-stocks 23 and 24 are also disposed in the position shown in full lines. However, when a relatively larger box is used, as indicated in broken lines, then the head members 29 are raised to the position shown in broken lines so that the top 5 of the box can be supported in open, substantially horizontal position. Obviously, one or any desired number of head-stocks may be used depending upon the size of the pack-

ing bench and/or the length of the shipping boxes.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. A packing bench comprising means for supporting a shipping box adapted to receive articles to be packed therein including an upwardly and rearwardly inclined back member and a bottom member inclining rearwardly and downwardly to said back member and cooperating therewith to form a cradle for receiving said shipping box, said box being provided with a top connected to one side thereof, and means carried by said box

15 supporting means for supporting the top of the said box in open substantially horizontal position to form a platform for receiving a stack of paper sheets which are to be used in the packing of the articles.

2. A packing bench comprising means for supporting a shipping box adapted to receive articles to be packed therein including an upwardly and rearwardly inclined back member and a bottom member inclining rearwardly and downwardly to said back member and cooperating therewith to form a cradle for receiving said shipping box, said box being provided with a top connected to one side thereof, and vertically adjustable means carried by said box supporting means for supporting the top of the said box in open substantially horizontal position to form a platform for receiving a stack of paper sheets which are to be used in the packing of the articles.

3. A packing bench comprising means for supporting a shipping box adapted to receive articles to be packed therein including an upwardly and rearwardly inclined back member and a bottom member inclining rearwardly and downwardly to said back member and cooperating therewith to form a cradle for receiving said shipping box, said box being provided with a top connected to one side thereof, and vertically adjustable head member carried by said box supporting means for supporting the top of the said box in open substantially horizontal position to form a platform for receiving a stack of paper sheets which are to be used in the packing of the articles, and means for securing said head member in desired adjusted position.

4. A packing bench comprising means for supporting a shipping box adapted to receive articles to be packed therein including an upwardly and rearwardly inclined back member and a bottom member inclining rearwardly and downwardly to said back member and cooperating therewith to form a cradle for receiving said shipping box, said box being provided with a top connected to one side thereof, means carried by said box supporting means forming a vertical guideway, a vertical bar slidable in said guideway, a head member carried at the upper end of said bar and adapted to support the top of the said box in open substantially horizontal position to form a platform for receiving a stack of paper sheets which are to be used in the packing of the articles, and means for securing the said bar in different positions of vertical adjustment to support the tops of shipping boxes of different sizes in open substantially horizontal position.

5. A packing bench comprising front and rear

and opposite side walls, said side walls having rearwardly and downwardly inclined edges and upwardly and rearwardly inclined edges, a bottom member secured upon said rearwardly and downwardly inclined edges and a back member secured to said upwardly and rearwardly inclined edges, said bottom member and back member being arranged at substantially right angles to one another to form a cradle for supporting a shipping box adapted to receive articles to be packed therein, said box being provided with a top connected to one side thereof, and means carried by said rear wall for supporting the top of the said box in open substantially horizontal position to form a platform for receiving a stack of paper sheets which are to be used in the packing of the articles.

6. A packing bench comprising front and rear and opposite side walls, said side walls having rearwardly and downwardly inclined edges and upwardly and rearwardly inclined edges, a bottom member secured upon said rearwardly and downwardly inclined edges and a back member secured to said upwardly and rearwardly inclined edges, said bottom member and back member being arranged at substantially right angles to one another to form a cradle for supporting a shipping box adapted to receive articles to be packed therein, said box being provided with a top connected to one side thereof, and vertically 30 adjustable means carried by said rear wall for supporting the top of the said box in open substantially horizontal position to form a platform for receiving a stack of paper sheets which are to be used in the packing of the articles.

7. A packing bench comprising front and rear and opposite side walls, said side walls having rearwardly and downwardly inclined edges and upwardly and rearwardly inclined edges, a bottom member secured upon said rearwardly and 40

downwardly inclined edges and a back member secured to said upwardly and rearwardly inclined edges, said bottom member and back member being arranged at substantially right angles to one another to form a cradle for supporting a shipping box adapted to receive articles to be packed therein, said box being provided with a top connected to one side thereof, a vertically 5 adjustable head member carried by said rear wall for supporting the top of the said box in open substantially horizontal position to form a platform for receiving a stack of paper sheets which are to be used in the packing of the articles, and means for securing said head member in desired 10 adjusted position.

8. A packing bench comprising front and rear and opposite side walls, said side walls having rearwardly and downwardly inclined edges and upwardly and rearwardly inclined edges, a bottom member secured upon said rearwardly and downwardly inclined edges and a back member secured to said upwardly and rearwardly inclined edges, said bottom member and back member being arranged at substantially right angles to one another to form a cradle for supporting a shipping box adapted to receive articles to be packed therein, said box being provided with a top connected to one side thereof, means carried by said rear wall forming a vertical guideway, a vertical bar slidable in said guideway, a head member carried at the upper end of said bar and adapted to support the top of the said box in open substantially horizontal position to form a platform for receiving a stack of paper sheets 20 which are to be used in the packing of the articles, and means for securing the said bar in different positions of vertical adjustment to support the tops of shipping boxes of different sizes in open substantially horizontal position.

DONALD F. MERCER.
